UNITED STATES PATENT OFFICE

1,941,361

AIR INLET CONTROL AND METHOD OF
OPERATING A PUMP-TURBINE

Lewis Ferry Moody, Princeton, N. J.

Application March 14, 1931. Serial No. 522,592

2 Claims. (Cl. 253—122)

This invention relates to hydraulic machines and particularly to an improved method of operation of machines of the reversible pump-turbine type in changing from turbine to pump operation and vice versa, and includes improved air control mechanism for use in carrying out this method as well as for use in hydraulic machines such as turbines or pumps in general.

In the operation of hydraulic turbines it is often desirable to unwater the rotor to permit driving the machine with minimum friction losses. For instance, when a turbine-generator unit operates as a synchronous condenser the turbine gates are closed and the vacuum in the draft tube broken by admission of air thereto so as to unwater the runner, thereby allowing the runner to rotate freely in the air. The admission of this air is effected usually automatically in accordance with the gate position. In the case of reversible pump-turbines, or of pumps alone sometimes, it is desirable to control air admission for the purpose of priming the pump or to insure stability and smoothness of operation. The automatic air control equipment heretofore used for turbines alone does not have that degree of flexibility of operation to render it efficient or entirely adapted for both turbine and pump operations.

Hence it is one object of my invention to provide an air control mechanism having an improved arrangement of elements so constructed and coordinated in their functions that the desired degree and timing of air control may be had for either turbine, pump or reversible pump-turbine units.

A further object is to provide an improved arrangement whereby the usual automatic air control may be had for turbine operation but with an improved control adapted to supplement the automatic control either by acting as an adjustment of the automatic control or of effecting air control independently of the position of the automatic control. Another and more specific object of the invention in this respect is to have the cooperating control subject to manual operation and preferably operable independently of the automatic control such, for instance, as not being movable upon operation of the automatic control and vice versa.

A still further specific object is to provide an improved air valve mechanism wherein the valve seat and cooperating valve member are each movable not only with respect to the valve casing but also with respect to each other.

A further object is to provide an improved air

admission control for a reversible pump-turbine so that the hand operation of the air valve may be used in starting and synchronizing the unit when operating as a pump whereby the machine may be started and synchronized with the runner revolving in air and with the guide vanes closed, after which the air inlet may be closed by hand and the runner space be allowed to fill with water. For low settings of the runner, below tailwater level, compressed air may be connected to the air valve and the water forced out of the runner space, with a second, hand operated, valve to relieve the air pressure after starting; or the compressed air may be admitted through a second valve with the air vent valve as shown herein used for relief after starting, the latter being usually the preferable arrangement.

A further and more specific object of my invention is to provide a valve seat adjustably rotatable so that the gate position for closure or opening of the air valve may be definitely adjusted by a hand wheel or if desired adjusted by a motor operated through a remote control.

Another object is to provide an improved method for changing from turbine to pump operation or vice versa.

Other objects and advantages will be more apparent to those skilled in the art from the following description of the accompanying drawing wherein:

Fig. 1 is a partial plan view of my improved arrangement applied to a turbine of either the Francis or high specific speed propeller types having wicket gates for controlling the flow to the runner although other usual types of gates could be employed;

Fig. 2 is a vertical section through the valve, its operating mechanism and part of a Francis turbine; and

Fig. 3 is a partial plan view of the valve and the operating gear.

Fig. 4 is a fragmentary vertical section of a modified form of the valve adapted for the use of compressed air.

The invention as specifically illustrated herein may be applied to different types of turbines, such as the Francis or high specific speed types, by having the adjustable gate mechanism operatively connected with my improved arrangement whereby an air admission valve may be controlled either automatically in accordance with a given position of the gate mechanism or manually independently of the gate position. The application of the invention to turbines having either wicket, plunger or cylinder gates will

be clear from one specific form of the invention described herein where wicket gates 1 are indicated in dotted lines and operated through usual gate arms 2 pivotally connected to connecting links 3 which in turn are pivotally connected to and actuated by a usual shifting ring 4. This ring and the adjustable or wicket gates 1 are disposed, as is well known, concentrically to the axis of runner R. Any suitable power means 10 such as a piston and cylinder motor, connected to a pivot 5 of the shifting ring, may be employed to oscillate the shifting ring to adjust the wicket gates to their open or closed positions. It is seen that either the movement or position of shifting ring 4 represents the movement or position of the wicket gates. Hence in the broader aspect of the invention the shifting ring, adjustable guide vanes and any associated linkages may be considered as gate or flow control mechanism. 15 The shifting ring and associated linkages are as shown in Fig. 2 disposed above the usual turbine head cover 6.

To admit air within the runner passage P, preferably directly to the draft tube as through 20 suitable openings in the head cover or runner, an inlet 7 provided with a ball-check valve is connected to any desired portion of the turbine passage and this inlet is controlled by an air valve mechanism. This valve mechanism is rigidly supported on the head cover 6 and includes 25 a base 9 having a central boss 10 supported either by a disk 9a provided with openings 9b or by radial arms. A valve seat 11, rotatably supported upon a stud 12 threaded in boss 10, has suitable sliding contact with base 9 so as to be 30 sufficiently leakproof. If desired the base 9 may have an axial flange 13 partially encircling the seat 11 so as not only to increase the effectiveness against leakage but also prevent dirt or 35 other foreign matter gaining access to the sliding surfaces. The seat has a series of openings 14 angularly spaced so as to provide alternate closed portions 15 of substantially similar extent to the openings. A portion of the periphery of 40 this seat is provided with a gear segment 11a which meshes with a hand wheel operated pinion 11b, the hand wheel pinion being carried by base 9. The gear ratio is preferably such as to cause upon one revolution of the hand wheel an 45 angular displacement of seat 11 substantially equal to the angular extent of the openings 14.

Also rotatably supported on stud 12 is a movable valve element 16 having openings 17 adapted 50 to register with the openings 14. Openings 17 likewise are angularly spaced so as to have closed portions therebetween whereby the openings 14 may be covered when desired.

An arm 18 normally fixed to the hub of valve 16 by a set screw 18a but adapted to be freely rotatable thereon upon loosening of the set screw, carries a roller 19 disposed within a slot 20 which is formed in a plate 21, this in turn being secured preferably to the inside of the shifting ring 4 as by bolts 22. As seen in Fig. 1 the cam slot 20 has a substantial arcuate portion concentric to the axis of the shifting ring 4 and a small offset portion 23. By loosening the set screw a complete independence is had between the two controls.

In turbine operation it is desired to open the air admission valve when the gate mechanism is in closed position. In this case the openings in both the valve seat and movable valve element 16 are in register which has been effected due 60 to roller 19 having engaged the surface of offset

cam slot 23, this cam surface having been moved into engagement with the roller when the shifting ring 4 was moved to closing position by the gate operating servo-motor. With the air valve thus open the draft tube will be vented and the 80 turbine allowed to rotate freely in air. When the gates open to a predetermined position, determined by the length of the arcuate slot 20, the air valve will close. The arcuate slot thus delays closing of the air valve so that air is admitted to 85 the draft tube during initial part-gate operation of the turbine, this being desirable.

If the hydraulic machine is a reversible pump-turbine and it is desired to change its operation from turbine to pump, the machine will be 90 brought to a stop and the generator operated as a motor in the reverse direction, it being understood that the runner preferably has fixed blades or at least blades which are not adjustable past each other, thus necessitating reverse direction 95 of runner rotation for pump operation. With the machine now running in the reverse direction for pump operation and with the gates still closed and the vent open, the pump is primed by first closing the air control valve, this being possible 100 in my improved arrangement notwithstanding that the gate mechanism is in closed position and the arm 18 is held against movement by roller 19 being in engagement with the offset cam slot 23. The valve is closed merely by rotating the hand wheel operated pinion 11b, thereby shifting the valve seat 11 relative to the other valve element 16 until the openings 17 of the latter are closed. Any suitable mechanism may 105 now be employed to prime the pump either by 110 an injector or other usual arrangements. After the pump is primed the gates are opened so as to permit pump discharge therethrough. If, during opening of the gates, the valve element 115 16 is actuated by the cam so as to tend to open the air inlet then the hand wheel control may again be superimposed on the action of the automatic control so as to maintain the valve closed. If for any reason during pump operation it should be desired in order to establish stability or 120 smoothness of operation, the air control valve may be opened to any desired extent.

It is thus seen that I have provided a very simple arrangement of parts whereby air control may be obtained for either pump or turbine operation by 125 employing elements which are common to both operations, thus providing a structure which is economical in initial cost of construction and of maintenance in addition to having a wide range of flexibility as is necessary in a reversible pump-turbine machine. It is also to be noted that in the specific valve shown one valve element acts as a seat while the other is the movable valve element and vice versa.

In some cases it may be desirable, in order to 130 provide means for holding the air valve closed independently of the action of the gate operating mechanism and cam, to use the stationary disk 9a instead of just radial arms. The disk has openings registering with those in the movable seat 11 140 so that when the seat 11 is rotated by the hand-wheel so as to place the openings in 11 above and in line with those in 9a, the openings will be controlled entirely by the operating mechanism and cam acting upon the valve disk 17. When the seat 11 is rotated so that its closed portions cover the openings in 9a, the valve remains closed independently of the motion of the valve disk 17 and of the turbine gates. Also, if seat 11 is adjusted to give a certain maximum opening then this can never 145 150

be made larger by the movement of valve 17 although it might be made smaller thereby. If instead of using a disk 9a, radial supporting arms are provided so as to have an opening over the 5 whole area then the operation is as previously described.

In the Fig. 4 modification a suitable cover 25 encloses the valve mechanism and operating gear, whereby compressed air may be supplied from any 10 source through an inlet 26. In this figure is also shown a means of remote control by the use of an electric motor 27 geared to the valve spindle, and having a sliding pinion 28 for disengaging the motor drive to permit manual operation by 15 the handwheel when desired. It will be understood that a similar remote control device can be applied to the other forms of valve illustrated, so that it is unnecessary to repeat this portion of Fig. 4 in the other figures as its application to 20 them will be obvious.

In the case of propeller turbines having adjustable runner blades such as is shown, for example, in my copending application, Serial No. 33,940, it is also possible, and may in some cases be desirable, to have the air admission valve actuated or controlled by the runner blade position rather than by the guide vane position. In describing the air valve as being controlled by the "adjustable gate mechanism" I therefore intend to include its 25 control by runner blade adjustment since such runner blade adjustment has the effect of controlling the flow and may be considered to supplement or replace the control by the guide vane adjustment, being in the nature of a gate mechanism in which the runner blades perform the additional function of gates while in motion with the remainder of the runner. Adjustable runner blades may be used as the sole flow control means 30

of a turbine, with the guide vanes stationary and combined with the casing stay vanes. In this case the adjustable air vent will be controlled by the runner blade adjusting mechanism.

It will of course be understood that various changes may be made in the construction, arrangement and operation of parts and of the device as a whole, without departing from the spirit of my invention as set forth in the appended claims.

I claim:

1. A hydraulic machine comprising, in combination, a runner, a passage therefor, adjustable gate mechanism for controlling the flow through said passage, an air inlet for said passage, means for controlling said air inlet automatically in accordance with a predetermined gate position, and means for additionally controlling the admission of air to said passage notwithstanding that the gate mechanism is in said predetermined position and having provision for determining the maximum extent of automatic air admission and of limiting the same if desired. 90

2. A hydraulic machine comprising, in combination, a runner, a passage therefor, adjustable gate mechanism having actuating means, an inlet through which air is admitted to said runner passage, a valve mechanism for said inlet, operating connections between said gate and inlet valve mechanism whereby the valve mechanism is adjusted automatically in accordance with the gate operation, and means for additionally controlling said air inlet while said operating connections remain in normal operative condition and having provision for limiting the maximum extent of 100 automatic air admission. 105
